UNITED STATES PATENT OFFICE.

MELANCTHON E. ZELLER, OF BLUFFTON, OHIO.

HARNESS-BUCKLE.

SPECIFICATION forming part of Letters Patent No. 738,650, dated September 8, 1903.

Application filed March 4, 1903. Serial No. 146,187. (No model.)

To all whom it may concern:

Be it known that I, MELANCTHON E. ZELLER, a citizen of the United States, residing at Bluffton, in the county of Allen and State of Ohio, have invented certain new and useful Improvements in Harness-Buckles; and I do hereby declare the following to be a full, clear, and exact description of the invention, such as will enable others skilled in the art to which it appertains to make and use the same.

My invention relates to certain improvements in harness-buckles generally, more particularly, however, to what may be termed "billet-buckles."

15 Said invention has for its object, among other things, to dispense with the riveting or similarly fastening of said parts in effecting the connecting up of the same for use, also to simplify and to facilitate the application 20 of the same for use.

The nature of the invention consists of the combination and arrangement of parts substantially as hereinafter more fully disclosed, and specifically pointed out by the claims.

25 In the accompanying drawings, illustrating the preferred embodiment of my invention, Figure 1 is a longitudinal section thereof. Fig. 2 is a detached side view of the frame or loop portion thereof. Fig. 3 is a plan view 30 with the parts extended.

Latitude is allowed herein as to details, as the same may be changed as circumstances suggest without departing from the spirit of my invention and the same remain intact and be protected.

35 In carrying out my invention I provide a frame or loop 1, produced, preferably, with angular lateral bars 1^a, an end bar 1^b, and at the opposite end with a plate extension 1^c and 40 intermediately of its ends with a second cross-bar 1^d, arranged laterally of a plane passing through said end cross-bar and plate.

Said end plate is preferably constructed so as to form a recess or bearing 2^a in its outer 45 surface to receive the tongue-bar of a buckle 3, as shown, said plate also having about centrally thereof an opening 2^b for the passage of the buckle-tongue therethrough. Said plate has also preferably cast therewith at 50 one edge a stud or projection 4, projecting laterally therefrom and having itself an extension 4^a at right angles thereto adapted to

be passed through an opening in a strap 5, forming part of the strap fastening or loop, said extension engaging said strap laterally, 55 thus effectually securing the strap as against displacement when in use. Said strap is also passed inwardly of the intermediate cross-bar of said frame or loop and through said buckle, receiving the tongue thereof, as shown, said 60 strap thus, together with said plate of the loop or frame, being held in place ready for use as desired.

Having thus described my invention, what I claim as new, and desire to secure by Letters 65 Patent, is—

1. In a device of the character described, the combination of a frame having an end plate, a buckle adapted to bear laterally upon said plate, and means connected up with said 70 frame and buckle to form a loop, said plate having a downwardly-projecting stud effecting connection between said plate and said loop.

2. In a device of the character described, 75 the combination of a frame having an intermediate cross-bar, an end plate or cross-piece, a buckle adapted to bear laterally upon said plate, and means connected up with said plate and buckle adapted to form a loop, said plate 80 or cross-piece having a downwardly-projecting stud adapted to effect connection between said loop and frame.

3. In a device of the character described, 85 the combination of a frame having an end cross-bar, an intermediate cross-bar, an end plate, a buckle adapted to bear laterally upon said plate, and a strap passing through said frame under said end cross-bar inwardly of said intermediate cross-bar, said plate having 90 a downwardly-projecting stud adapted to effect connection between said strap and said frame.

4. In a device of the character described, 95 the combination of a frame having an end plate provided at one edge with a downwardly-projecting stud having an extension at right angles thereto, a buckle adapted to bear laterally upon said plate, and a strap adapted to be connected with said frame by means of 100 said stud, said extension of said stud bearing laterally upon said strap.

5. In a device of the character described, the combination of a frame having an end

plate extension provided with a lateral recess, a buckle having its tongue-bar engaging said lateral recess and its tongue passing through an aperture in said plate extension, and a strap, said end plate extension having a downwardly-projecting stud adapted to effect connection between said strap and said frame.

6. In a device of the character described, the combination of a frame having an end ¹⁰ extension-plate provided with a lateral recess, a buckle having its tongue-bar engaging said recess and its tongue passing through an aperture in said plate extension, a strap, said plate extension having a lateral stud at one ¹⁵ edge, said stud having a right-angled extension and passing through said strap, said extension laterally engaging said strap.

7. In a device of the character described, the combination of a frame having angular ²⁰ lateral bars, an end bar, an intermediate cross-bar arranged laterally of a plane passing through said end bar, said frame also having an opposite end plate extension, said plate extension having at one edge a downwardly-projecting stud provided with a forward extension at right angles thereto, and a strap passing intermediately of said cross-bars and end plate extension and adapted to receive said stud with its terminal or extension standing laterally of said strap.

8. In a device of the character described, a buckle-strap-carrying frame or loop, having an apertured end plate extension provided with a laterally-deflected end stud adapted to ³⁵ pass through the strap and laterally engage said strap, said plate forming a bearing for the buckle and its aperture receiving the buckle-tongue.

9. In a device of the character described, a buckle-strap-carrying frame having an apertured end plate extension provided with a laterally-deflected end stud adapted to pass through the strap and laterally engage said strap, said end plate extension forming a bearing for the buckle and its aperture receiving the buckle-tongue, said frame also having an end cross-bar and an intermediate cross-bar arranged in a plane laterally of said cross-bar and end plate extension.

10. In a device of the character described, a buckle-strap-carrying frame having an apertured laterally-bent end plate extension provided with a right-angled stud adapted to pass through the strap and laterally engage said strap, said plate adapted to form a bearing for the buckle and its aperture adapted to receive the buckle-tongue.

11. In a device of the character described, a strap-carrying frame having a laterally-bent end plate extension provided with an aperture and a right-angled stud adapted to pass through the strap and laterally engage said strap, and a buckle, said plate extension forming a bearing for said buckle, and said aperture adapted to receive the tongue of said buckle, said frame also having an end cross-bar and an intermediate cross-bar arranged in a plane laterally of said end cross-bar and said end plate extension.

In testimony whereof I affix my signature ⁷⁰ in presence of two witnesses.

MELANCTHON E. ZELLER.
